MANUFACTURE OF SOAP

Ashton T. Scott, Ardmore, Pa., and Leopold Sender, Baltimore, Md., assignors to The Sharpies Corporation, Philadelphia, Pa., a corporation of Delaware

Application November 4, 1941, Serial No. 417,748

8 Claims. (Cl. 260—418)

The present invention relates to the art of soap making, and was conceived primarily as a method of making soap continuously with the aid of centrifugal separators. Processes for the manufacture of soap by passing a saponifying reagent continuously into confluence with a source of fat, saponifying the fat by passage of the mixture at saponifying temperature continuously through mixing apparatus, and separating spent reagent from fat by centrifugation are described and claimed in the co-pending applications of Ashton T. Scott, Serial No. 333,547, filed May 6, 1940, and Serial No. 334,297, filed May 10, 1940. The present invention is primarily a development of the procedure of these two co-pending applications resulting in improved mixing of reagent with the source of fat and improved yield of soap, by which these results may be obtained without impairment of the product.

In the processes of the above-mentioned applications of Ashton T. Scott, the fat is continuously saponified by treatment with a saponifying reagent such as lye, the saponification being accomplished by intensely mixing the fat and lye while passing them at a saponifying temperature through closed mixing apparatus under super-atmospheric pressure. The resulting soap-containing mass is maintained under intensive agitation practically up to the moment when it is passed into a centrifugal separator for removing the aqueous reagent phase from the soap. The saponification is preferably accomplished in a plurality of counter-current stages, and the removal of the soap from the zone of centrifugation is accomplished by mixing water or saponifying reagent with the soap while it is still in a turbulent condition due to discharge from the zone of centrifugation. The soap is grained, and thus conditioned for removal of the aqueous phase, prior to centrifugation, by the addition of a salt solution, or an excess of saponifying reagent which serves as a salting out agent. In the process of application Serial No. 334,297, the salting out operation is accomplished simultaneously with the saponification by addition of the salting out agent before the start of the saponification reaction.

At the conclusion of the final saponification step of the above-mentioned Scott applications, the soap from the centrifugal of the last saponification stage is mixed with water, and also with electrolyte if necessary, to change the grained or curd soap to a neat soap and at the same time form a new phase which is known as nigre. The

neat soap and nigre are thereafter separated from each other by centrifugation.

By the practice of the present invention, the economics of the Scott process are improved by returning the nigre from the centrifugal by which it is separated from neat soap to one of the saponification stages of the process. By operating in this manner, the nigre, which contains a large proportion of soap, serves to emulsify the saponifying reagent with the source of fat to be saponified, thereby improving the contact between reagent and fat and speeding up the saponification reaction. At the same time, the soap contained in the nigre is recovered from the saponified mass in one of the centrifugals by which the aqueous reagent phase is separated from soap in the cycle of mixing and centrifugal separating steps constituting the saponification stages of the soap making operation.

In accordance with modifications or amplifications of the above procedure, the invention may be practiced by separating dirt from the nigre and neat soap as a third effluent in the fitting operation by which the nigre is separated from the neat soap. The separate removal of dirt in this manner effects a still further improvement in the process, since, after separation of dirt, the nigre may be returned to one of the earlier saponification stages and combined with further fat and alkali with a minimum of contamination by dirt from the preceding saponified mass which has already been subjected to fitting.

In a still further modification or amplification of the process, the nigre may be subjected to a further, and separate, centrifugal clarifying operation, before being recycled to the saponification stage.

The nature of the improvements constituting the features of the invention, and the manner in which the invention is practiced, will be better understood by reference to the following specification when considered in connection with the attached flow sheet, in which,

Figure 1 represents a simple form in which the invention may be practiced,

Figure 2 illustrates a slight modification or amplification of the process of Figure 1, and

Figure 3 represents a further modification or amplification.

In the practice of the invention as illustrated in Figure 1, fat from container 10 is passed into confluence with a saponifying reagent, such as lye from container 11. The fat and lye are passed together, preferably under super-atmospheric pressure, through a mixer 12, which is heated to

a temperature (e. g., 200° F.) sufficiently high to effect saponification of most of the fat during passage through the mixer. The mixture is maintained in a state of intensive agitation in order to insure rapid saponification of the fat, and fluidity of the mixture until it is passed into centrifugal 13. The soap is grained prior to passage to the centrifugal 13, this graining being accomplished either by adding a graining agent in a separate step to the substantially saponified mass, as in Scott application Serial No. 333,547, or by adding a graining agent to the mixture before saponification commences, as in Scott application Serial No. 334,297. In either case, an aqueous saponifying reagent phase, which may be spent lye containing impurities removed from the partially saponified mass, is removed continuously as one effluent from the centrifugal 13, and grained soap, containing a small proportion of unsaponified fat, is removed as a second effluent from that centrifugal.

The grained soap from centrifugal 13 is continuously mixed with a further quantity of saponifying reagent, preferably by injection of the saponifying reagent directly to the cover of the centrifugal in order to assist in discharge of the grained soap from the centrifugal and intimately mix the saponifying reagent therewith while the soap is in a turbulent condition due to discharge from the centrifugal. In any case, the mixture of grained soap and residual unsaponified fat with fresh saponifying reagent is passed through a mixer 15 and subjected to saponifying and graining steps prior to passage to a second centrifugal 16, which effects separation between partly spent lye and grained soap similar to the separation effected in the centrifugal 13.

The grained soap discharged from centrifugal 16 may next be mixed with water from container 17 in mixer 21, this water being added in sufficient quantity to effect the fitting operation by which the grained soap is converted into a mixture of neat soap and nigre. A part of the water used to effect the fitting operation may be discharged into the cover of the centrifugal 16 to assist in discharge of the grained soap from that cover.

The nigre is separated from the neat soap in centrifugal 18, and most of the dirt and other impurities contained in the soap discharged from the centrifugal 16 are removed from the neat soap in this step, as will be well understood by those skilled in the art.

The steps discussed above in connection with the elements 10 to 18 of the flow sheet are disclosed in the co-pending applications of Ashton T. Scott which have been discussed. In the practice of the present invention, nigre from centrifugal 18 is returned from that centrifugal to one of the saponification stages involved in treatment of further quantities of fat with saponifying reagent. Since this nigre is derived from a centrifugal treatment involving application of a force many thousand times the force of gravity in centrifugal 18, a large part of the dirt will ordinarily be separated from the nigre as well as the neat soap in this centrifugal treatment, thereby providing a nigre which is of considerably higher quality than the nigres obtained by the kettle soap making process. In view of this fact, the nigre may be returned to one of the saponification stages over a prolonged cycle of operation in the practice of the process, without becoming so contaminated with impurities as to impair the quality of the neat soap materially in the continued practice of the process. The process may

be practiced by returning the nigre into the saponification cycle prior to the practice of the first saponification step, as indicated by the reference character 19, or it may be returned prior to the second saponification step as indicated by the reference character 20. The point at which the nigre is returned to the saponification cycle will depend largely upon the manner in which the saponification steps are conducted, upon the concentration of the reagent used in these steps, for example. A part of the nigre may be returned at point 19, and another part at point 20, as indicated by the flow sheet of Figure 1. As a still further alternative, a part, or all, of the nigre may be returned to the second saponification stage at point 22, after substantial completion of the saponification reaction of that stage, the soap value of the nigre being recovered by the centrifugal 16 in such an operation, but the nigre not passing through the step of the stage in which the saponification is accomplished. As pointed out above, when the nigre is returned at a point in one of the saponification stages prior to the zone of saponification, it assists in emulsifying the saponifying reagent with fat, but the advantages of the invention may be partially attained, insofar as recovery of soap values is concerned, even by return of the nigre at point 22; i. e., to a point in the cycle of operations subsequent to completion of the entire saponification reaction.

Figure 2 illustrates an operation in which a centrifugal 30 provided with special discharge outlets for separated dirt is substituted for the centrifugal 18. In the practice of the embodiment of the invention illustrated in this figure the impurities separated from the nigre are discharged through special outlets extending from the inner circumferential wall of the rotor, while the nigre and neat soap are continuously discharged separately from these impurities and from each other. In this embodiment of the invention, as in the embodiment of Figure 1, the nigre may be returned to the saponification cycle at the points 19, 20 or 22, or separate parts of it may be returned at all three of these points, or any two of them. In removal of impurities from the nigre and neat soap, if the soap-containing mixture being subjected to the fitting operation contains a substantial amount of free alkali, it will be desirable to add a source of organic or inorganic acid, in order to neutralize a part or all of the free alkali, since the dirt and other impurities may be best separated from the nigre when it is in a substantially neutral condition, or contains at most only a very small amount of free alkali. A feature of the invention therefore consists in addition of a source of acid, which may be an organic or inorganic acid or an ester (e. g., a saponifiable fat) from container 31, and heating of the mixture after addition of this source of acid in the mixer 21 in order to assist in neutralization of free alkali and thereby convert the nigre into a condition in which a large proportion of the dirt may be separated from it in the centrifugal 30 or the centrifugal 18. While this feature of addition of a source of acid is particularly valuable in connection with the practice of the process in cases in which the nigre is recycled to one of the saponification stages, it has value as a step for producing a nigre of improved purity regardless of whether the nigre is recycled to an earlier saponification stage of a continuous process, and a part of the present invention consists in the addition of a source of acid in performance of the centrif-

ugal fitting step per se, regardless of whether the other features of the invention are practiced.

As a still further modification or amplification of the process of Figure 1, the nigre from the centrifugal 18 or 30 may be subjected to a separate centrifugal clarifying step before being returned to the saponification cycle, as illustrated in Figure 3 of the drawings. Thus, the nigre, after removal from the centrifugal 18 or 30 may be passed through a centrifugal 40 which serves to clarify the nigre further by removal of dirt and other impurities therefrom, and the clarified nigre may then be returned to the saponification cycle as discussed above. In case such a separate clarifying step is performed upon the nigre before recycling it, a modifying agent, which may be water or a source of acid as discussed above, is preferably added to the nigre before it is passed to the centrifugal 40. The dilution of the nigre with water frees a part of the impurities remaining in the nigre after discharge from the centrifugal 18 or 30, and these impurities may then be removed by passage of the nigre through the centrifugal 40. In case this separate clarifying step is performed, the preferred procedure involves mixing a source of acid with the nigre in the mixer 41 by passing such source of acid from container 42 into confluence with the nigre, and heating the mixture to facilitate neutralization or partial neutralization of free alkali by the source of acid. The step of clarification by addition of a source of acid to reduce the free alkali followed by centrifugation is not claimed per se as a feature of the present application, since it is covered in a separate application filed in the joint names of Leopold Sender and James H. Wilson, Serial No. 389,888, filed April 23, 1941. Regardless of whether water or a source of acid be used as the agent to assist in the centrifugal clarification of the nigre by the centrifugal force, however, the addition of a modifying agent and performance of a separate step of centrifugal clarification of the nigre is valuable in the practice of the present invention, since it enables us to recycle the nigre with a minimum of contamination of the soap-containing mass with which it is mixed in the recycling operation.

Various modifications will be obvious to those skilled in the art, and we do not therefore wish to be limited except by the scope of the following claims.

We claim:

1. In the manufacture of soap, a process comprising accomplishing a saponifying stage by mixing a source of fat with a saponifying reagent, subjecting the resulting mixture to saponifying reaction conditions, salting out the soap to produce a soap phase and an aqueous phase, and thereafter subjecting the resulting mixture to centrifugation to separate the soap phase from aqueous phase as the final step of said saponifying stage, thereafter mixing the grained soap and unsaponified fat derived from said saponifying stage with a further quantity of saponifying reagent and subjecting the resulting mixture to a second saponifying stage including the same steps as said first-mentioned saponifying stage, thereafter fitting the grained soap derived from said second-mentioned saponifying stage by mixing said grained soap with water and separating nigre from neat soap by centrifugation, and returning nigre derived from said last-mentioned centrifugation to the first-mentioned saponifying stage in treatment of a further quantity of a

source of fat with a further quantity of saponifying reagent in the manufacture of a further quantity of soap.

2. In the manufacture of soap, a process comprising accomplishing a saponifying stage by mixing a source of fat with a saponifying reagent, subjecting the resulting mixture to saponifying reaction conditions, salting out the soap to produce a soap phase and an aqueous phase, and thereafter subjecting the resulting mixture to centrifugation to separate the soap phase from aqueous phase as the final step of said saponifying stage, thereafter mixing the grained soap and unsaponified fat derived from said saponifying stage with a further quantity of saponifying reagent and subjecting the resulting mixture to a second saponifying stage including the same steps as said first-mentioned saponifying stage, thereafter fitting the grained soap derived from said second-mentioned saponifying stage by mixing said grained soap with water and separating nigre from neat soap by centrifugation, and returning nigre derived from said last-mentioned centrifugation to the second-mentioned saponifying stage in treatment of a further quantity of a source of fat with a further quantity of saponifying reagent in the manufacture of a further quantity of soap.

3. In the manufacture of soap, a process comprising accomplishing a saponifying stage by mixing a source of fat with a saponifying reagent, subjecting the resulting mixture to saponifying reaction conditions, salting out the soap to produce a soap phase and an aqueous phase, and thereafter subjecting the resulting mixture to centrifugation to separate the soap phase from aqueous phase as the final step of said saponifying stage, thereafter mixing the grained soap and unsaponified fat derived from said saponifying stage with a further quantity of saponifying reagent and subjecting the resulting mixture to a second saponifying stage including the same steps as said first-mentioned saponifying stage, thereafter fitting the grained soap derived from said second-mentioned saponifying stage by mixing said grained soap with water and separating nigre from neat soap by centrifugation, and returning nigre derived from said last-mentioned centrifugation to the second-mentioned saponifying stage at a point in the cycle of operations subsequent to the saponifying reaction of said second-mentioned saponifying stage in treatment of a further quantity of a source of fat with a further quantity of saponifying reagent in the manufacture of a further quantity of soap.

4. In the manufacture of soap, a process comprising accomplishing a saponifying stage by mixing a source of fat with a saponifying reagent, subjecting the resulting mixture to saponifying reaction conditions, salting out the soap to produce a soap phase and an aqueous phase, and thereafter subjecting the resulting mixture to centrifugation to separate the soap phase from aqueous phase as the final step of said saponifying stage, thereafter mixing the grained soap and unsaponified fat derived from said saponifying stage with a further quantity of saponifying reagent and subjecting the resulting mixture to a second saponifying stage including the same steps as said first-mentioned saponifying stage, thereafter fitting the grained soap derived from said second-mentioned saponifying stage by mixing said grained soap with water and separating nigre from neat soap by centrifugation, and returning nigre derived from said last-mentioned

centrifugation to the first-mentioned saponifying stage at a point in the cycle of operations prior to the saponifying reaction of said first-mentioned saponifying stage in treatment of a further quantity of a source of fat with a further quantity of saponifying reagent in the manufacture of a further quantity of soap.

5. In the manufacture of soap, a process comprising accomplishing a saponifying stage by mixing a source of fat with a saponifying reagent, subjecting the resulting mixture to saponifying reaction conditions, salting out the soap to produce a soap phase and an aqueous phase, and thereafter subjecting the resulting mixture to centrifugation to separate the soap phase from aqueous phase as the final step of said saponifying stage, thereafter mixing the grained soap and unsaponified fat derived from said saponifying stage with a further quantity of saponifying reagent and subjecting the resulting mixture to a second saponifying stage including the same steps as said first-mentioned saponifying stage, thereafter fitting the grained soap derived from said second-mentioned saponifying stage by mixing said grained soap with water and separating nigre from neat soap by centrifugation, and returning nigre derived from said last-mentioned centrifugation to the second-mentioned saponifying stage at a point in the cycle of operations prior to the saponifying reaction of said second-mentioned saponifying stage in treatment of a further quantity of a source of fat with a further quantity of saponifying reagent in the manufacture of a further quantity of soap.

6. In the manufacture of soap, a process comprising accomplishing a saponifying stage by mixing a source of fat with a saponifying reagent, subjecting the resulting mixture to saponifying reaction conditions, salting out the soap to produce a soap phase and an aqueous phase, and thereafter subjecting the resulting mixture to centrifugation to separate the soap phase from aqueous phase as the final step of said saponifying stage, thereafter fitting grained soap derived from the saponifying reaction by mixing said grained soap with water and with a source of acid and neutralizing free alkali of the mixture by said source of acid and thereafter separating nigre from neat soap and impurities by centrifugation, and returning nigre derived from said last-mentioned centrifugation to a saponifying stage in treatment of a further quantity of a

source of fat with a further quantity of saponifying reagent in the manufacture of a further quantity of soap.

7. In the manufacture of soap, a process comprising accomplishing a saponifying stage by mixing a source of fat with a saponifying reagent, subjecting the resulting mixture to saponifying reaction conditions, salting out the soap to produce a soap phase and an aqueous phase, and thereafter subjecting the resulting mixture to centrifugation to separate the soap phase from aqueous phase as the final step of said saponifying stage, thereafter fitting grained soap derived from the saponifying reaction by mixing said grained soap with water and separating nigre from neat soap by centrifugation, thereafter adding water to the nigre and separating impurities from the nigre obtained by said last-mentioned step of centrifugation by a subsequent step of centrifugation, and returning nigre derived from said final step of centrifugation to a saponifying stage in treatment of a further quantity of a source of fat with a further quantity of saponifying reagent in the manufacture of a further quantity of soap.

8. In the manufacture of soap, a process comprising accomplishing a saponifying stage by mixing a source of fat with a saponifying reagent, subjecting the resulting mixture to saponifying reaction conditions, salting out the soap to produce a soap phase and an aqueous phase, and thereafter subjecting the resulting mixture to centrifugation to separate the soap phase from aqueous phase as the final step of said saponifying stage, thereafter fitting grained soap derived from the saponifying reaction by mixing said grained soap with water and separating nigre from neat soap by centrifugation, thereafter adding a source of acid to the nigre and neutralizing free alkali of the mixture by said source of acid and thereafter separating impurities from the nigre obtained by said last-mentioned step of centrifugation by a subsequent step of centrifugation, and returning nigre derived from said final step of centrifugation to a saponifying stage in treatment of a further quantity of a source of fat with a further quantity of saponifying reagent in the manufacture of a further quantity of soap.
